UNITED STATES PATENT OFFICE.

DALLAS R. MATTHEWS, OF CINCINNATI, OHIO.

ATTACHMENT FOR WASHING MACHINES.

Application filed February 14, 1925. Serial No. 9,171.

To all whom it may concern:

Be it known that I, DALLAS R. MATTHEWS, a citizen of the United States, residing at Cincinnati, in the county of Hamilton and State of Ohio, have invented certain new and useful Improvements in Attachments for Washing Machines, of which the following is a specification.

The present invention consists of an attachment for washing machines through the medium of which the labor of washing is reduced to a minimum and, co-ordinately, the cleansing of the washing cylinder may be performed in a facile and expeditious manner.

An object of the invention is to provide suitable mechanism applicable for use on standard types of washing machines to permit elevation of the relatively heavy and unwieldy clothes carrying cylinder to a point of accessibility at the top of the washing machine tub or casing.

Another object of the invention is to provide manual, or mechanical means for raising the cylinder, of a cylinder type washing machine, out of its tub or casing to bring the cylinder into proximity to the operator, especially for convenience in removing clothes from the cylinder, for cleaning or repairing the cylinder, and for the purpose of completely removing the cylinder from its bearings in the tub.

Other objects of the invention will be apparent from the following description of the present preferred form of the invention wherein:—

Fig. 1 is a side elevational view of mechanism constructed in accordance with the present invention illustrating its application on a cylinder type washing machine;

Fig. 2 is a detail enlarged fragmentary sectional view of the same;

Fig. 3 is an end elevational view of the mechanism illustrating its application on a washing machine, the latter being shown partly in section;

Fig. 4 is a detail enlarged fragmentary sectional view of a washing machine tub or casing illustrating the manner of mounting the mechanism thereon;

Fig. 5 is a detail fragmentary perspective view of the cylinder saddle comprising a part of the present invention;

Fig. 6 is a detail enlarged fragmentary sectional plan view of a washing machine embodying the present invention; and

Fig. 7 is a detail perspective view of a washing machine bearing block constructed in accordance with the present invention.

It is well known in this art to provide mechanisms for elevating a washing machine in its entirety and it is furthermore well known in the art to so construct the washing cylinder and mount it in its tub or casing in such a manner that it may be elevated independently of the tub or casing. The present invention is consequently limited to the means employed for elevating the clothes cylinder independently of the tub or casing in which the cylinder is mounted.

In order to illustrate the application of the present invention a tub or casing 8 is shown which may be of any desired configuration and may be mounted upon a mobile base in a manner well known in the art. In use of the present invention, however, it is desired that a block 10 be mounted on the inner face of each end of the tub or casing 8, which block, as illustrated to advantage in Fig. 7 of the drawings, is provided with a V-shape recess 11 in its upper terminal and is provided with a vertical slot 12 in its outer face. A washing cylinder 13 also of conventional design is mounted in the tub or casing 8 and is equipped with terminal pintles 14 which rest in the V-shape recesses 11 of the blocks 10 when the cylinder is mounted in the tub or casing as shown in Fig. 1.

The essential parts of the mechanism employed for elevating the cylinder 13 embody a saddle 15 which latter is composed of a single metal strap bent into substantially U-shape, the base of which is in parallelism with the bottom of the casing 8 while the terminals are parallel to the ends of said casing. The free ends of said terminals are provided with recesses 16 which are adapted to receive the pintles 14. The terminals of the saddle are slidably mounted in the grooves 12 of the blocks 10 so that when pressure is exerted upon the base of the saddle the cylinder 13 will be elevated in an obvious manner. Said terminals are held from displacement by guide strips 15, one of which is mounted on each of the blocks 10 and straddles the groove 12 thereof.

The means employed for exerting pressure on the saddle consists especially of a rod 17 the upper end of which extends con-

centrically through an annulus 18 formed on the bottom of the casing 8 and also extends through an opening formed in said casing bottom. Said upper terminal of the 5 rod 17 is secured to the base of the saddle 15 preferably at a point approximately midway the ends of said base as illustrated to advantage in Figs. 1 and 2. The diameter of the inner periphery and the annulus 18 is relatively larger than the diameter of the 10 rod 17 and is provided with screwthreads which complement and are adapted to engage a packing nut 19 through which the rod 17 passes. The nut is, of course, adjustable so that packing material mounted in the housing may be compressed from time to time to avoid leakage from the casing and to minimize the possibility of lateral movement of the rod. The lower end of the rod 15 20 has a pulley wheel 20 journaled therein. Said pulley wheel has the intermediate portion of a cable 21 trained thereabout, one end of the cable being secured to the bottom of the casing 8, as indicated at 22, while the opposite end is trained about a pulley 23 journaled on the bottom of the casing 8 and passes therefrom into engagement with a drum 24 which is also journaled on the bottom of the casing 8. The drum in the 30 present instance is shown as being operated by a hand crank 25 but this is for the purpose of illustration only, since numerous other expedients may be employed for rotating the drum.

35 In use of this device, assuming that the cylinder 13 is mounted in the casing 8 in the manner shown in Fig. 1 of the drawings, it can be elevated by simply turning the crank 25. As is apparent, rotation of the crank 25 correspondingly rotates the drum 24 and winds the cable 21 thereon. This exerts pressure on the pulley 20 and urges the rod 17 upwardly through the packing nut 19. The saddle 15 is simultaneously elevated as 40 is also the cylinder 13 by reason of the fact that upward movement of the saddle disengages the pintles 14 from the blocks 10. The cylinder may be raised to any desired position and held there through such means as a pawl 26 and serrations in the crank 25 which it engages. As is apparent, this permits the cylinder to be elevated in a facile and expeditious manner for removing the clothes from the cylinder, or for permitting the removal of the cylinder from the casing. 45 In this way, the cylinder can be cleaned or repaired, and access readily gained thereto for any other purpose. It eliminates the labor now entailed by the operator of a washing machine, especially the cylinder type, in view of the fact that after the washing has been completed the operator must bend over and reach down into the cylinder casing or tub to remove the cylinder pintles 50 from the casings in the tub after which the

cylinder is manually removed from the casing to permit the latter, as well as the cylinder, to be cleaned out before the next washing operation. Since the cylinders are relatively heavy, operators frequently experience difficulty in removing them and very often subject themselves to injuries. The present device, however, permits the cylinder to be elevated to a point above the casing where it may be conveniently grasped 70 and removed by any one capable of operating a washing machine.

75 It is, of course, to be understood that I have herein described simply a preferred form of the present invention. The essence 80 of the invention is to employ the present mechanism or its substantial equivalent to elevate the cylinder, whether the means employed for operating the mechanism be mechanical or electrical. The present device, 85 as illustrated in the drawings, is adapted for use on a standard cylinder type washing machine but it is to be understood that the mechanism forming the present invention may be varied to adapt the same for use on 90 other types of washing machines.

95 What is claimed is:—

1. An attachment for cylinder type washing machines including a tub equipped with bearings, a cylinder having terminal pintles mounted in said bearings, a saddle mounted in said tub the ends of which embrace the pintles, and means movable through the bottom of the tub and engageable with said saddle for elevating the cylinder to the top 100 of the tub.

105 2. In combination with a washing machine tub equipped with a clothes cylinder having terminal pintles mounted in bearings in the tub; means for elevating said cylinder including a saddle the ends of which are 110 slidable through said pintle bearings and engage with said pintles for disengaging the latter from their bearings.

115 3. In combination with a tub equipped with bearings and a clothes cylinder with pintles engageable in said bearings, a saddle engageable with said pintles and movable bodily through the bearings for elevating the cylinder, and a rod extending through the bottom of said tub and engaged with said saddle and movable vertically through the tub substantially as described.

120 4. A washing machine attachment, in combination with a washing machine tub equipped with a rotatable clothes cylinder provided with terminal pintles mounted in bearings on the ends of the tub; mechanism for elevating the cylinder including a saddle the ends of which are slidable through the pintle bearings and embrace said pintles, and means engaged with said saddle to urge 125 the same upwardly.
